RAIL ANCHOR

Albert F. Fifield, Cleveland, Ohio, assignor to The American Fork and Hoe Company, Cleveland, Ohio, a corporation of Ohio

Application February 21, 1946, Serial No. 649,150

3 Claims. (Cl. 238—329.)

1

My invention relates to two-piece rail anchors of the "Stead" type and, more particularly, involves an improvement in the pre-assembled type of "Stead" rail anchors which is exemplified by the disclosures of United States Letters Patent No. 2,022,880 to F. W. Cooper issued December 3, 1935.

Commonly, earlier types of "Stead" rail anchors comprised a channel-shaped clamp member having its arms notched inwardly from a forward edge to provide upper and lower jaws adapted to embrace one flange of a rail base, and provided with a web convergingly upwardly inclined relative to the plane of the rail base, engaging surfaces of the lower jaws, and a looped spring retaining member comprising a long upper arm terminating forwardly in an upturned hook and its rear portion being curvilinearly joined to a relatively short lower arm directed convergingly forwardly and upwardly towards an intermediate portion of the upper arm and the lower surface of the short arm being adapted to rest upon the upper surface of the clamp member web; also, in such anchors, the retaining spring member being formed from a strip of flattened spring steel, was of lesser width than the space between the inter-spaced channel arms, so that the anchor members were assembled only after the clamp member was affixed to the rail flange.

The looped retaining spring of said prior rail anchors by virtue of its looped form providing a great over-all length and its inherent ability to resiliently flex under the varying conditions of application and use has, in the past, largely contributed to the popularity of such anchors.

In the said patented pre-assembled type of "Stead" anchors, the means provided for maintaining the clamp and spring members in pre-adjusted relative positions, ready for unitary application to a rail base, resided in providing each of both arms with an intermediately disposed substantially abrupt inwardly directed offset affording a shoulder which extended from the front to the rear edges of said arms in a direction parallel to, but spaced somewhat below, the plane of the surfaces of the lower jaws.

Such offset or shoulder served to provide each of the channel arm with upper and lower portions, both of the upper and both of the lower clamp arm portions being relatively parallel, with all opposing surfaces of the upper portions being disposed closer together than those of the lower portions, and the width of the upper arms of the spring member being such that the considerable length of said upper arm, which was disposed between the upper arm portions, made close fric-

tional engagement with the inner surfaces of said portions, while the lower and shorter spring arm is in close frictional engagement with the channel web.

Such a construction well served the purpose of affording a unitary pre-assembly of the clamp and retainer spring members, but at the disadvantage of achieving a substantial degree of immobilization of the retainer spring loop whereby the anchor after application to a rail base was forced to largely depend upon that portion of the length of the long spring arm which was disposed forwardly of the clamp member for, resilient yielding, responsive to the forces imposed upon the spring during application to the rail base, and thereafter imposed thereon under the severe conditions of rail anchor use.

However, inasmuch as the high degree of efficiency achieved in the early type of "Stead" rail anchors, in large part, has resulted from the use of a retaining spring made from a bar whose normal effective length is generally about twice the width of the rail base, it is important that in use no such considerable portion of such length is so immobilized as to substantially reduce such resiliently effective length.

In the anchor of my present invention, the upper arm portions of the channel clamp are so skewed relative to the lower portions that they are interspaced a lesser distance in the region of the rear edges of said arms, than is the case in the other portions thereof proceeding towards the forward edges of the upper arm portions, whereby the lateral edges of a portion of the longer arm of the spring member is compressively resiliently compressed only between the relatively converged rearmost inner surfaces of the arms, which thus frictionally engage the extremely short length of the upper arm in the region of the curvilinear loop which interconnects the spring arms.

The rail anchor of my invention is thus not only one adapted to achieve a pre-factory assembly of the parts in operative relation to one another to effect a unitary structure adapted for shipment, rough handling and application to a rail as a unit without additional relative readjustment of its members, but also is adapted to effect such a unitary structure in a manner which will not interfere with free resilient deflection of the various parts of the looped spring member during application of the anchor to the rail nor thereafter during the various operative conditions of use.

By virtue of my present invention, all parts of the spring member loop and all parts of the two arms embraced by the channel shaped clamp

arms with the exception of one point at the two sides of a rearmost portion of the long arm is free of lateral compressive engagement by the inner surfaces of the channel arms.

An object of my invention therefore is to provide an improved preassembled "Stead" type rail anchor wherein no restraint against deflection of the long arm of the looped spring retaining member is occasioned as a result of an improved construction whereby a preassembled two-piece anchor is achieved, the benefits of preassembling being thus achieved without loss of resiliency of said spring retaining member.

Another object of my invention is to provide an improved form of a preassembled "Stead" type rail anchor wherein the provisions made for pre-assembly are efficiently effective and at the same time without loss of operative efficiency due to the provision of the operative elements relied upon to accomplish such preassembly.

Other objects of my invention and the invention itself will become more apparent to those skilled in the art to which my invention appertains by reference to the accompanying drawings which illustrate a single embodiment of my invention wherein:

Figure 1 is a view in side elevation of the rail anchor of my invention applied to a rail base, the bottom being shown in transverse vertical section.

Fig. 2 is a pictorial view of the two parts of the anchor in Fig. 1, in assembled relation, ready for application to a rail base.

Fig. 3 shows, in tilted view, pre-assembled anchor parts in an initial stage of application to the rail base, the view otherwise being as in Fig. 1.

Fig. 4 is a top plan view of the parts as shown in Fig. 2.

Figs. 5 and 6 are respectively rear and front elevational views taken from the respective planes *c-c* and *d-d*, indicated in Fig. 4.

Referring more particularly to the drawing, 11 designates a railroad rail having the usual base flanges 12 and 13, and Fig. 1 shows my improved rail anchor comprising a clamp member 16 and a spring retaining member 17 therefor, applied to said base flanges.

The spring member is formed of a preferably flat bar of spring metal bent flatwise intermediate its ends to provide a substantially curved loop portion 18, a long upper arm 19 and a short lower arm 20 converging toward a medial portion of the upper arm. The extremities of the upper and lower arms terminate in upwardly turned hook portions 21 and 22. The long arm is formed with a reversely curved portion 23 adjacent the loop and a slightly downwardly bowed portion 24 between the reversely curved portion 23 and the upstanding hook 21, the bowing preferably being such that said portion 24 of the long arm curves downwardly toward and then upwardly away from the end of the short arm.

The short arm may be substantially straight between the loop 18 and the hook 22 and lies in such angular relation to the long arm that the tip of the hook 22 is normally spaced below the long arm, when the member is relaxed, as shown in Fig. 3. The two arms and the loop constitute a resilient structure, wedge-shaped in its vertical aspect of which the loop constitutes the butt or large end.

The clamp member is channel-shaped, as shown in Fig. 2, being preferably formed by bending a flat sheet of metal, to provide a web portion 25 forming a seat for the spring mem-

ber and two upstanding arms 26 each notched in a forward edge, as at 27, to afford upper and lower jaws adapted for reception of a rail base flange, such as the flange 12. The vertical depth of the notches is preferably such that the thinnest rail base flange for which the clamp is adapted will be a close fit in the notches without bottoming.

Preferably, the lower jaw surfaces 28 provided by the lowermost edge of the notches 27 lie in a plane which is disposed at a substantial angle to the plane of the clamp web 25, the upper jaw surfaces 29 provided by upper edge portions of the notches are disposed at such an angle to said lower jaw surfaces, as to grippingly engage a rail base flange to which said jaws are applied, initially most tightly in portions of the upper and lower surfaces of said flange which are disposed substantially inwardly from the flange edge, thereby to minimize any tendency to weaken the edge portions of said flange.

The lower rearward end of the web 25 is preferably provided with an upward projection 33, which may be most conveniently formed by upward stretching displacement of the metal of the web which is disposed midway between the junction of said web and the channel arms.

The channel clamp member of my invention differs from prior constructions in such manner as to efficiently adapt it for preassembly with the retainer spring but without resultant immobilization of the spring action of the clamp enclosed portion of said spring. This, I have achieved by effecting front-to-rear convergence of the opposing inner surfaces of the upper portions of the two channel arms only in what I term the "upper zone" which comprises all portions of the free ends of the two arms which are disposed above the line A-A' of Fig. 1. The rearward portions of the opposing surfaces of the said two arms disposed in said upper zone are therefore disposed more closely together than the opposing surfaces thereof which are relatively disposed nearer the front edges of said arms.

The line A-A' of Fig. 1 which is preferably parallel to and spaced somewhat below the plane of the lower jaw gripping surface, taken in conjunction with the line B-B' defines an acute angle which includes a shoulder 32 of gradually diminishing depth and up-and-down extent which is of greatest depth and extent at the rearmost edge portions of the channel arms and which preferably terminates in the region of the junction of said lines, said shoulder 32 being interposed between upper and lower zone portions of the channel arms and affords an off-setting junction between the lowermost relatively parallel arm portions 261 and the uppermost relatively front-to-rear converging portions 262.

The clamp member of my present embodiment therefore is in channel form with its arms presenting a pair of preferably substantially straight and parallel front edges, though interrupted by the notches 27, and a pair of relatively straight and parallel lowermost rear edge portions which are disposed below the shoulder 32 with a pair of inwardly offset rear edge upper portions disposed above said shoulder.

The rail anchor of the described embodiment is therefore of the "pre-assembled Stead" type and employs the conventional "Stead" type of rearwardly looped resilient flat bar steel spring retaining member shown generally at 17, wherein a substantially C-shaped rearmost loop connector 18 joins the pair of relatively forwardly converg-

ing relatively long and short spring arms 19 and 20.

The prior conventional type of "pre-assembled Stead" rail anchor is best typified by the anchor disclosed in the aforesaid Cooper patent.

The clamp member hereof is distinguished from said prior anchor in that only the opposing inner-surface portions of said clamp arms, which are nearest the rearmost edges of the arms and which are located in an upper portion of said arm, are converged to a maximum degree.

In this manner the portions 262 of the inner-surfaces of the arms 16, which are most closely relatively interspaced, are located adjacent the rearmost edges of the clamp arms 16 only in portions thereof which are located at least as far distant from the predominant plane of the web 25, and excluding the web tongue 33, as are the most forward portions of the lower jaw surfaces 28.

The width of the bar from which the spring retaining member is formed is such that when positioning the spring retaining member between the clamp arms, relatively opposite lateral edge portions of the spring arm 17, wedgingly engaged until the most closely converged, relatively confronting inner surfaces of the clamp arms in those portions of said clamp arms are adjoining the rearmost edges of the channel arms in said upper zone, whereby the arms will resultantly be forcibly spread apart an amount equal to the excess of width of the interposed portions of the spring member over the normal distance between the converged rearmost portions of the inner surfaces of the two arms in said upper zone.

In the present embodiment the spring bar is substantially of uniform length throughout, and while such uniformity of width is preferred, my invention is not limited to precise uniformity of the spring bar width.

To achieve preassembly of the two anchor parts at the factory, this may be best accomplished by either introducing the hooked end of the long arm of the retaining member between the clamp arms close to the web from the rearmost side of the clamp, and then pressing the retaining member forwardly in such manner as to project the rail flange retaining hook 21 into the approximate plane of the lowermost jaw gripping surfaces, or, if desired, a midportion of the lower short arm 29 of the retaining member may be hand-placed between the upper and forward corners of the clamp member arms with said short arm preferably disposed in a plane parallel to that of the lower jaw gripping surfaces and then applying the power of a press to the upper side of the long arm of the retaining member in such a direction as to accomplish the same positioning of the spring member within the clamp as according to the first method.

The transversely resiliently effected grip by the converged rearward inner surface of the aforesaid upper portions of the arms just above the shoulder 32 is sufficient to hold the two parts rigidly in the established relation against any force tending to alter such relation which would ordinarily be encountered in hand shipping and distribution for application to a rail base.

For practical purposes, the two parts of the anchor are maintained in unitary relationship ready for application to a rail base, yet, since the retainer spring is only gripped at a single extremely short portion of its length by the clamp side arms, the two parts are capable of relative movement for adjustment to a rail, and all por-

tions of the retaining spring are as well adapted for such ready flexing of its various portions as in the case of the early type of non-assembled "Stead" anchors and throughout all of the varying conditions of actual use, the various parts of the spring retaining member are capable of being flexed without undue restraint by the one point lateral engagement of the clamp side arms with the side edges of said retaining member.

In the factory assembly, the spring member is advanced through the clamp member until the end of the long arm hook 21 is approximately flush with the surfaces 28 of the clamp jaws, as shown in Fig. 3. The vertical and horizontal grip of the clamp member on the spring member is sufficient to hold the two parts rigidly in the established relations against greater force tending to alter the relation than will ordinarily be encountered in handling, shipment and distribution for application. In short, the two parts are so rigidly related that for all practical purposes of handling, they are as much a unit as if formed of a single piece of metal. Yet the parts of the unit are capable of relative movement for adjustment to a rail, or, if necessary, for separation.

The wedging camming effect of the converging surfaces 32 causes the spring member to assume the relation to the clamp member illustrated in Fig. 3 during insertion in the clamp member and also serves to maintain this relation which is that desired as a preliminary to application to a rail.

The semi-rigid factory assembled unit, shown in Fig. 3, is applied to a rail by manually passing the projecting spring member arm 24 beneath a rail while holding the clamp, so that notches thereof receive the edge of one rail base flange, one arm of the clamp member being held in close engagement with the side of a tie. This manual application may be effected without resistance to slightly more than the extent shown in Fig. 3, that is, until the upward swing of the advancing end of the unit caused by the notches taking position on one base flange brings the end of the hook 21 against the bottom of the other base flange close to the edge thereof. The application is continued forcibly, as by striking the projecting loop 18 with a hammer.

This application of force urges the spring member to advance through the clamp and is also transmitted to the clamp principally by frictional engagement of the lower arm 29 with the inclined web of the clamp. The transmission of force to the clamp being entirely beneath the rail, the lower end of the clamp is swung inwardly and upwardly about a pivotal point at the engagement of the corner 31 with the upper surface of the base flange and causes the clamp to move to its final relation to the rail, as shown in Fig. 1.

This swinging movement relieves the tendency of the clamp corners 31 to bite into the flange and, if desired, further relief may be obtained by a slight chamfering of the corner 31. As the spring member advances through the clamp, its looped end is subjected to vertical compression both by reason of its wedging action between the converging web and offsets and by reason of its upward movement on the inclined web, bringing the top of the loop into engagement with the bottom of the rail base. At the same time, the aforesaid upward swing of the clamp member bodily raises the spring member and thrusts the hook 21 against the bottom of the rail base flange 13 and causes the long arm of the spring member to be flexed with straightening tendency, so that by the com-

binced compression and arm flexion, the space between the short arm hook 22 and the long arm is closed and thereafter upward movement of the hook 22 due to climbing on the inclined web and to upward swing of the clamp is transmitted in its entirety to the long arm.

It has been stated that movement is transmitted from the spring member to the clamp member chiefly through the bottom arm of the spring member, and this is due to the increasing inclination of the web, as the clamp swings, and to the fact that the upward swing for a time raises the inner ends of the offsets 32 at about the same rate that the upper arm of the spring member rises. As the spring member advances through the clamp, the resistance increases by reason of further compression of the loop between the projection 33 and the bottom of the rail base flange 12 and also by reason of the increasing inclination of the web due to the inward swing of the clamp.

Before any very great increase of resistance is manifest, the point of maximum depth of the loop passes the top of the projection 33 and the loop commences to travel down the inwardly facing incline of the projection and by expansion maintains its contact with the bottom surface of the rail base flange 12. This downward movement tends to offset the resistance to further advance due to the increase in the inclination of the spring path, and also tends to cause the entire spring member to swing in a vertical plane about its line of support at the inner edge of the web, so that the hook 21 is thrust upwardly against the bottom of the rail base flange 13 close to the edge thereof with additional force and, as actual upward movement of the hook is prevented, the swinging tendency of the spring member causes additional flexion of the arm 19 with further straightening tendency.

The combined advance of the spring member through the clamp and the bodily inward movement and inward swing of the clamp member as aforesaid cause the hook 21 to pass the edge of the rail base flange and to be raised into engagement with the edge surface of the flange by the upward swing of the spring arm and held by the tension thereof.

A few taps directed against the upper rearward corners of the clamp member may then, if the spring member has been accidentally overdriven, cause it to recoil so that the hook 21 is drawn tightly against the rail flange edge.

The described structure involving inward spring pressure engagement between a very limited portion of the length of the spring arm disposed in the downwardly bowed portion 23 with correspondingly small areas of the most inwardly converged inner surfaces of the clamp arms, achieves applicant's objective of eliminating substantial immobilization of the reactive spring action of said long arm 19 which previously has adversely affected the ability of the anchor to be retained in place upon a rail base under severe conditions of usage involving up-and-down movement of the rails when traversed by trains, said up-and-down movements sometimes causing the lower surface 25 of the clamp to forcibly engage underlying road ballast materials and tending to turn the clamp, together with the spring 19, in a clockwise direction, as viewed in Fig. 1. Such momentary clockwise movement in the prior assembled "Stead" type of anchors has had the effect of depressing the hook 21 sufficiently to loosen said hook from its associated side of the rail base, and

in many cases, under conditions of hard or frozen, substantially high road ballast underlying the rails, "Stead" anchors have become dislodged from the rail base.

5 In the present construction, however, the longer effective length of the spring arm 19 is sufficient to maintain the hook 21 in place, and dislodgement of the anchor from the rail, under above described conditions, does not occur.

10 So far as the mere semi-permanent assembly of the parts to resist separation is concerned, the existence of the projection 33 is not material nor is this projection material to the establishment and maintenance of the desired relation of the
15 parts for application purposes, since this effect is produced by the relation of arm convergence to the points of support of the spring member on the web and, by suitably positioning or forming the converging arm surfaces, the desired effect may
20 be produced with any lower projection and obviously, the height of the projection may be reduced to nothing. The projection is, however, to facilitate application by reducing the inclination of the path of the spring member.

25 Having thus described my invention, I am aware that obvious departures from the precise form of the illustrated embodiment of my invention may be made without departing from the spirit of my invention and such obvious departures are within the scope of my invention as defined by the claims.

I claim:

1. In a two-piece rail anchor, the combination of a spring retainer member of substantially uniform width formed from a flat steel bar, said bar being bent to provide an uppermost long spring arm terminating forwardly in an upturned hook and a relatively short lower spring arm integrally joined to the rear end of the long spring arm and extending forwardly and upwardly to dispose its free end below a medial portion of the long spring arm, a U-shaped clamp formed of flat steel to provide a pair of upstanding clamp arms and a web interconnecting the lowermost portions of said clamp arms, the lower end portions of said clamp arms being disposed substantially parallel to each other and another more upwardly disposed portion of both said clamp arms being inwardly skewed in the rearward direction to cause the relatively opposing inner surfaces of said clamp arms which are disposed nearest the rear edges of such relatively upper clamp arm portions to be more closely interspaced than any other opposed inner surfaces of the clamp arms, each of said clamp arms being correspondingly notched inwardly and upwardly from an intermediate portion of their forward edges to afford, by the upper and lower notch edges, a pair of relatively divergent upper and lower rail-base flange jaw surfaces, said lower notch edges being disposed in a plane which is rearwardly divergent with respect to said web, the said opposed most closely interspaced inner surface of said clamp arms being disposed rearwardly of said notches and below the rearwardly extending plane of said lower notch edges, said retainer being insertable between the clamp arms with a rearwardly disposed portion of the upper arm wedged tightly between said closely interspaced opposed inner surfaces of said clamp arms and all other portions of the retainer member which are disposed between said arms, below said plane, and above said web, being free of lateral pressure engagement by any portion of said clamp arms, the said hook end of the long retainer arm being extended

forwardly from between said clamp arms, whereby the clamp and retainer members are unitarily interconnected for application to a rail base, said notches adapted to embracingly receive one flange of the rail base, and said long arm hook adapted to be snapped upwardly over the lateral edge of the other rail base flange, in response to driving pressure applied to the rearmost portion of said retainer.

2. In a rail anchor substantially of the two-piece type comprising the combination of a looped substantially resilient spring member of substantially uniform width having a long upper spring arm terminating forwardly in an upturned hook, a shorter lower spring arm extending forwardly in an upwardly converging relation to a medial portion of the upper arm, a rearmost C-shaped arm-connecting loop interconnecting said spring arms, with a channel-shaped clamp, said clamp comprising a pair of upstanding arms and a web connecting the lower portions of said arms, and both arms being so correspondingly notched inwardly and upwardly from an intermediate portion of their forward edges as to provide a pair of rearwardly convergent upper and lower notch edges respectively affording relatively upper and lower jaw surfaces, said lower jaw surfaces being disposed in a plane which is in forwardly convergent relation to said web, and said clamp arms comprising relatively upper and lower portions which are respectively successively disposed between said plane and said web, the said lower portions being substantially parallel and said upper portions being rearwardly convergent toward the rearmost edges of the clamp arms whereat the opposing inner surfaces of the said upper portions of the clamp arms which are adjacent the rear edges thereof and disposed adjacently below said plane are in more closely interspaced relation to each other than are any other opposing portions of said arms which are disposed between the plane containing said lower jaw surfaces and said web, said most closely interspaced opposing inner surface portion of the clamp arms being initially disposed more closely together than the width of the spring member, whereby said spring member and clamp may be pre-assembled with the looped portion of the spring member being forced between said clamp arms below the said plane of the said lower jaw surfaces, whereby said clamp arms will be resiliently spread apart by the interpositioning of a substantially short portion of the spring member, which is disposed in the general region of juncture between said connector and long arm portions, between said most closely interspaced and rearwardly disposed inner surface portions of the said relatively upper portions of said clamp arms, said clamp arms by resilient retractive effort tightly frictionally holding the spring member and clamp together for unitary application in the usual manner to a rail base, whereupon with one flange of the rail base being received between the sets of upper and

lower clamp jaw surfaces and with driving blows applied against the rearwardly exposed portion of the connector portion of said spring member, said upturned hook is adapted to be snapped upwardly over the opposite rail base flange edge of the rail base, and said spring member being otherwise, than aforesaid, free of lateral frictional engagement with any other inner surface portions of said clamp arms.

3. In a rail anchor of the two-piece type, a steel spring retaining member having a forwardly converging, rearwardly interconnected, pair of relatively superposed spring arms of which the lower spring arm is the shorter and is forwardly upwardly inclined toward a medial portion of the upper spring arm, a U-shaped clamp member having a pair of upstanding clamp arms and a web interconnecting the lower ends of said clamp arms, said arms being rearwardly and upwardly notched from a medially disposed portion of their forward edges in such manner as to provide for each arm a pair of forwardly divergent relatively upper and lower notch edge surfaces which are adapted to afford a pair of relatively superposed cooperative rail base flange embracing jaw surfaces, said clamp arms alike having relatively opposing inwardly displaced inner surface portions of substantially small area which are located substantially adjacent to rear edge portions of said clamp arms and substantially closely below a rearwardly extended plane which contains said lower jaw surfaces, all other opposing inner surface portions of said clamp arms, located below the said plane, being relatively more laterally interspaced than said inwardly displaced opposing surface portions thereof, rearwardly disposed portions of said retaining member being adapted, during pre-assembly of the members and also during unitary attachment of the assembled retaining and clamp members to a rail base, to be laterally embraced by said clamp arms, said embraced portions of said retaining member being of such a uniform width that a tight wedging frictional engagement is effected only between said inwardly displaced inner surfaces of said clamp arms and relatively short opposite lateral edge surfaces of an upper rearwardly disposed portion of said retaining member, all other lateral surface portions of the retaining member which are disposed between said clamp arms being adapted to fit loosely between more widely interspaced inner surface portions of said clamp arms.
